SPEED LIMIT CONTROL

Stewart E. Watterworth and Austin A. Quirk,
Bridgeport, Conn.

Application May 21, 1940, Serial No. 336,366

5 Claims. (Cl. 137—153)

This invention relates to a speed limit control device for automobiles, and has for an object to provide a simple and effective device to limit the speed of an automobile so that in ordinary driving it cannot be driven at a greater speed than that for which the device is set, but may be readily set for different speeds as desired, so that when a car is being driven where there are different speed zones the device may be set for the speed designated for a zone as the car enters that zone and the driver may operate with the assurance that the car will not be driven over that speed until the device is again set for another speed. He therefore is not required to watch the speedometer to prevent driving over the speed limit, and may give his entire attention to watching traffic and operating the car.

It is also an object to provide such a device which in an emergency may be readily operated to permit higher speeds if required to meet the emergency.

It is a further object to provide such a device for limiting the speed of the car to which the device is set, but in which the limit speed may be maintained in going up a hill as well as when driving on the level.

With the foregoing and other objects in view we have devised a construction illustrated in the accompanying drawing forming a part of this specification. It is, however, to be understood we are not limited to the specific details shown, but may use other constructions and arrangements within the scope of the invention.

In this drawing:

Fig. 1 is a side elevation of the device showing its relation to the carburetor and intake manifold of an automobile engine and showing the elements in the position they occupy when the engine is not running;

Fig. 2 is a top plan view of the device showing the elements in the position they assume when the engine is running;

Fig. 3 is a side elevation of a part of the device when in the position of Fig. 2; and

Fig. 4 is a similar view showing another position of the device.

In the drawing a portion of the carburetor is shown at 5 and a portion of the intake manifold is indicated at 6 with a connection 7 for conducting the mixture of gas and air from this carburetor to the manifold. This connection usually has a flange 8 connected to the flange 9 at the underside of the carburetor. In mounting my device these flanges may be separated sufficiently to mount the plate or block 10 form-

ing a part of my device between them, it being clamped between these flanges by any suitable means such as the bolts or screws 11 and gaskets 12 may be clamped between the flanges and the block 10 to secure gas-tight connection. Through the member 10 is a passage 13 in alignment with the passage from the carburetor to the connection 7 for passage of the mixture of gas and air. In this passage is a control valve 14, such for example as a butterfly valve mounted on a suitable shaft 15. This valve may be provided with a series of openings 16 therethrough to prevent cutting off entirely the flow of gases through the passage and also to prevent the pull of the flow of gases upsetting the balance.

Mounted on the shaft 15 is a lever 17 mounted on one end of which is a stud 18 through which passes a flexible wire 19 leading to a hand pull or adjusting knob 20 mounted where it is easily accessible to the driver while in driving position, as for example on the dash 21 in front of the driver. The stud 18 is mounted to turn on the lever 17 as this lever swings with the shaft 15, and the wire 19 has a sliding fit in the stud 18. Beyond the stud 18 is a stop collar 22 secured to the wire 19 by any suitable means such as a set screw 23 which will permit the collar 22 to be adjusted to the desired position on the wire. The wire is also preferably guided and protected by a flexible tubular casing 24 leading from a securing member 25 mounted on the block 10 by a bracket 26 secured to the plate by any suitable means, such as the bolts 27, to the dash 21. The flexible casing may be supported at an intermediate point by a collar 28 on a bracket 29 also mounted on the block 10. The member 25 is mounted to turn to permit the wire and casing to flex as its connection with the stud 18 moves through turning of the lever 17.

On the other arm of the lever 17 is a stud 30 mounted to turn relative to the lever, and through this stud extends a slidable rod 31 having a stop collar 32 thereon at one side of the stud 30 and a compression spring 33 at the other side pressing at its opposite ends against the stud 30 and a collar 34 on the rod 31. The collar 32 is secured on the rod by any suitable means such as a set screw 35 which will permit locating the collar at any desired location. The other end of the rod 31 is connected to a suitable suction operated device 36, which may for example be a piston in a cylinder, but preferably is a flexible diaphragm 37 in a suitable casing connected by a small tube 38 with the suction of the motor, preferably either at the bottom of the carburetor

or the intake manifold. In the present case it is shown connected at 39 to the connection 7 leading to the manifold. The suction in the casing 36 created through the pipe 38 tends to move the diaphragm 37 to the right or to the position shown in dotted lines Fig. 2, while a spring 40 tends to move it in the opposite direction and retain it in the position shown in dotted lines Fig. 1.

Normally when the engine is not running the parts are in the position shown in Fig. 1, the diaphragm 37 being shifted to the left under the action of the spring 40 shifting with it the rod 31 and through action of the collar 32 on the stud 30 through the lever 17 and the shaft 15 shifting the valve 14 to the open position as shown in full lines Fig. 1. Thus the spring 40 tends to shift the valve to the open position. Suction on the diaphragm 37 tends to shift it to the right and through action of the rod 31 tends to move the valve to closed position, and such action will take place as soon as the suction is sufficient to overcome the force of the spring 40. Movement of the valve toward closed position, however, is limited by the collar 22 on the wire 19 which forms a limit stop for the stud 18 mounted on the other arm of the lever 17. Thus the position of the valve 14 will take under action of suction on the diaphragm 37 is determined by the position of the collar 22, which position may be adjusted and determined by shifting the wire 19 by means of the hand knob 20, and the location and thus the position of the collar 22 determines the maximum speed at which it is desired that the motor be operated for any given adjustment of the hand knob 20.

Thus in operation the control valve 14 is set to a position for the maximum speed desired by shifting the hand knob 20 to the desired position which through the wire 19 sets the position of the collar 22. When the engine is not running this valve may be fully opened as shown in Fig. 1 due to the fact that as there is no suction on the diaphragm 37 this diaphragm is in its extreme left hand position. Thus the valve 14 does not prevent passage of gaseous mixtures from the carburetor to the intake manifold and therefore does not interfere with the operation of starting the motor. As soon as the motor starts the suction through the pipe 38 on the diaphragm 37 draws it forward or to the right to the position of Fig. 2 and draws the rod 31 forward with it so as to move the valve 14 to the limit to which the collar 22 on the wire 19 will let it go, this collar operating as a stop for the stud 18 on the lever 17. That determines the maximum speed for which the handle 20 and collar 22 is set. If the knob 20 is drawn out so as to position stop collar 22 to prevent the valve 14 from moving the whole distance with rod 31, which is true in Figs. 2 and 3, the spring 33 yields as shown to permit diaphragm 37 and rod 31 to make their full movement.

During normal operation the speed of the motor and the car up to this limit is controlled by the regular throttle valve and accelerator (not shown) in the usual manner. It will be seen that as the position of the valve 14 is thus set and determined, no more gas can be fed to the engine than would pass this valve for this setting, no matter how wide the regular throttle valve is opened, and therefore the speed of the car as controlled by the regular throttle or accelerator cannot be carried beyond this limit. Thus, for instance, if the position of the valve

14 of Figs. 2 and 3 corresponds to a maximum speed of 35 miles per hour, this valve is maintained in this position by the suction of the engine operating on the diaphragm 37, and no matter how wide the regular throttle valve is opened the speed of the car cannot be carried beyond this 35 mile limit, but the car can be driven with the usual accelerator at any speed up to this 35 mile speed limit.

10 If this opening of the valve 14 corresponds to the maximum speed of 35 miles per hour when driving on the level it will be clear that more gas must be supplied if this maximum speed is to be maintained in going up a hill. This condition is automatically taken care of by the suction device. As the car goes up the hill and the speed drops somewhat (say, one or two miles per hour) the suction decreases and this permits the diaphragm 37 and rod 31 to move to the left under action of spring 40 causing the collar 32 to engage the stud 30 and move it to the left, thus turning the shaft 15 and opening the valve 14 to allow more gas to flow into the manifold to keep up the speed. As soon as the speed again picks up to the 35 mile limit (in the example under discussion) the increased suction again draws the diaphragm 37 and rod 31 forward moving the valve 14 back to its original position. Practically the maximum speed may therefore be maintained under all conditions if desired.

15 If it is desired to set the maximum speed for a lower limit the knob 20 may be pushed inwardly shifting the wire 19 and collar 22 farther to the left, say, for example, to the position of Fig. 4 (dotted position 14a of Fig. 1) for a maximum speed of 25 miles per hour, the valve 14 being in this position across the passage 13. Then as the motor starts the suction on the diaphragm 37 will move the valve 14 to this position shifting it from the open position of Fig. 1. However, if in going up a hill the speed drops below this 25 mile limit the reduced suction permits the diaphragm 37 to move to the left carrying 20 with it the rod 31 to open the valve 14 (say, to position 14b or 14c, Fig. 1) by action of the collar 32 to supply the additional gas to keep the speed up to the limit, but as before, when the speed reaches the limit of approximately 25 miles the increased suction action on the diaphragm again closes the valve so that the speed is maintained at approximately 25 miles, or slightly under this limit.

25 Although with this device in ordinary driving the car cannot be driven above the maximum speed for which the device is set by the hand knob 20, if the driver should get into a jam, say, for example in passing another car, and should need a sudden burst of speed he could secure it by quickly pulling out the knob 20 farther, which through action of the collar 22 on the stud 18 would open the valve 14 to give the necessary increased supply of gas. The spring 33 would yield to permit this movement. Then after 30 he is out of the emergency the knob 20 can be set back to the maximum speed desired. Some means may be provided to retain the knob 20 and the wire 19 in adjusted positions. Thus the shank 20a of the knob may be provided with a series of suitably spaced notches or recesses 41 in which a spring pressed ball 42 may seat. Although this will retain the knob and wire in adjusted positions the ball will yield to permit of ready adjustment of the knob. The recesses 41 may be spaced to correspond with the different

increments of maximum speed limits desired, say, for example a difference of five miles between the different settings.

Thus it will be seen that with this device the driver can easily and quickly set the device to limit the maximum speed to that indicated for any given speed zone, and he can then continue to drive the car with the usual throttle and accelerator with the assurance that he will not go beyond the set speed limit, and he is not required to watch the speedometer with consequent detraction from the operation of driving. However, should a sudden burst of speed be required to meet an emergency this may be readily secured. Still further, substantially the maximum speed for which the device is set may be maintained not only in driving on the level but also in going up a hill or grade, as the extra amount of gas to maintain this speed on the grade is supplied automatically.

Having thus set forth the nature of our invention, what we claim is:

1. In a device of the character described, a block adapted to be mounted between the carburetor and the intake manifold of an automobile engine and having a passage therethrough for the gaseous mixture, a valve in said passage, a shaft on which the valve is mounted, a lever on said shaft, a rod having sliding connection with one arm of said lever, a suction operated device connected to said rod, a stop on the rod between the lever and the suction device and adapted to engage said lever to open the valve, a compression spring on the rod at the other side of the lever to permit the lever to move independently of the rod, a spring tending to shift the rod to open the valve, said suction device being responsive to suction to shift the valve toward closed position, a flexible wire having sliding connection with the other arm of the lever, a stop on said wire to limit closing movement of the valve under action of the suction device, and manually operable means adjustable from the driver's position to adjust the position of said stop.

2. In a device of the character described, a control valve adapted to be located between the carburetor and intake manifold of an automobile engine, a suction operated device, a rod connected with said suction device and having sliding connection with the valve, a stop on the rod to shift the valve toward open position, a spring on the rod permitting movement of the valve toward open position independently of the rod, a spring tending to shift the rod to open the valve, a passage in which the pressure is dependent on suction, means connecting the suction device to said passage to cause the suction therein to shift the valve toward closed position, and manually operable means adjustable from

the driver's position to limit closing movement of the valve under action of the suction device.

3. In a device of the character described, a block adapted to be mounted between the carburetor and the intake manifold of an automobile engine and having a passage therethrough for the gaseous mixture, a valve in said passage, means for operating the valve, a suction device, a connection from said suction device to said operating means having sliding connection therewith, means on said connection to positively engage the operating means to shift the valve toward open position, a spring on said connection through which the suction device may act to shift the valve toward closed position, means tending to shift said connection to open the valve, said suction device being responsive to suction to close the valve, and manually adjustable means to limit closing movement of the valve under action of the suction device.

4. In a device of the character described, a control valve adapted to be mounted between the carburetor and intake manifold of an automobile engine, a suction operated device, an operative connection from the suction device to the valve including a yieldable connection to transmit the force of the suction device and adapted to permit movement of the valve toward open position independently of the suction device, means tending to shift the valve toward open position, said suction device being responsive to suction to shift the valve toward closed position through said yieldable connection, and manually operable means adjustable from the driver's position to limit closing movement of said valve under action of the suction device and operable to shift the valve toward open position independently of said device.

5. In a device of the character described, a control valve adapted to be mounted between the carburetor and intake manifold of an automobile engine, a shaft on which the valve is mounted, a lever on said shaft, a suction operated device, an operative connection from the suction device to one arm of the lever adapted to permit movement of the valve toward open position independently of the suction device, means tending to shift the valve toward open position, manually operable means adjustable from the driver's position, a connection from the said manual means to the other arm of the lever having sliding connection therewith, and a stop on said connection to limit closing movement of the valve under action of the suction device and operable by said manual means to shift the valve toward open position independently of the suction device.
